UNITED STATES PATENT OFFICE.

CHARLES J. WALZ, OF NEW YORK, N. Y., ASSIGNOR, BY DIRECT AND MESNE ASSIGNMENTS, TO WEST DISINFECTING COMPANY, A CORPORATION OF NEW YORK.

DISINFECTING APPARATUS.

SPECIFICATION forming part of Letters Patent No. 788,805, dated May 2, 1905.

Application filed November 1, 1904. Serial No. 230,983.

To all whom it may concern:

Be it known that I, CHARLES J. WALZ, a citizen of the United States, residing in New York city, borough of Manhattan, New York, have 5 invented certain new and useful Improvements in Disinfecting Apparatus, of which the following is a specification.

My invention relates to improvements in the class of disinfecting apparatus in which the 10 disinfecting fluid is gradually fed from a reservoir to the open air for evaporation and delivery in small quantities to the place to be disinfected; and the object of my invention is to provide means for controlling at will the 15 amount of fluid to be distributed and to provide for the more equal distribution of the fluid for evaporation.

My invention comprises a casing provided 20 with a fluid-containing reservoir, a fluid-receiving chamber, means to regulate at will the height of the fluid to be delivered to said chamber from the reservoir, means for transferring fluid from the chamber, and means for receiving such fluid and causing its distribution.

The invention also comprises the novel details of improvement that will be more fully hereinafter set forth and then pointed out in the claims.

Reference is to be had to the accompanying drawings, forming part hereof, wherein—

Figure 1 is a side elevation, partly broken, of a disinfecting apparatus embodying my invention. Fig. 2 is a plan view thereof, part 35 of the cover being removed. Fig. 3 is a vertical section substantially on the line 3 3 in Fig. 2. Fig. 4 is a detail of a modified form of the valve for controlling the flow of fluid from the main reservoir to the receiving-chamber, and 40 Fig. 5 is a sectional detail showing a cap for the main reservoir.

Similar numerals of reference indicate corresponding parts in the several views.

The numeral 1 indicates a casing, which 45 may be cylindrical in form, having a bottom 2 and an interior transverse partition 3, forming a chamber 4, and between which bottom 2 and partition the sides or wall of the casing

1 are perforated, as at 1^a. Above the partition 3 is a main fluid-containing reservoir 5, 50 which is shown contained between an upper partition 6, an inner wall 7, the lower partition 3, and the outer walls or sides of casing 1. The wall 7 opens through the top partition 6 and forms a chamber 8 in conjunction with part 55 of the casing 1 and the lower partition 3. (See Fig. 2.) The wall 7 at its lower portion has a vertically-disposed opening 7^a, which in Fig. 3 is shown in the form of a slot providing communication between reservoir 5 and chamber 60 8, and I provide a valve device (shown located in chamber 8) to control the flow of fluid from reservoir 5 to said chamber. For this purpose I have shown a tube 9 disposed vertically in chamber 8 and provided with opposed 65 openings 9^a 9^b, shown in Fig. 3 in the form of vertically-disposed slots on opposite sides of tube 9, said tube being secured fluid-tight to the wall 7, so that its opening 9^a alines with opening 7^a in said wall to permit the passage 70 of fluid from reservoir 5 to chamber 8. Within tube 9 is a valve stem or rod 10, which is screw-threaded to mesh with corresponding threads within tube 9, said tube being threaded throughout its length, the threads on rod 75 10 extending along the same sufficiently far to enable said rod to be screwed down to positively close the passage through openings 9^a 9^b throughout their whole length. Rod 10 may have a squared end or the like 10^a to receive a key inserted through the open end of chamber 8 to permit operating said rod. When rod 10 is screwed outwardly the desired distance, fluid from reservoir 5 will flow 80 through opening 7^a 9^a 9^b into chamber 8 to the 85 height at which the lower end of rod 10 remains. Instead of having slots 9^a 9^b in tube 9 said tube may be provided with a series of vertically-disposed perforations, (indicated at 9^c.)

The partition 6 is shown provided with an 90 opening 6^a, having a threaded neck 6^b, receiving a threaded plug 11, that is provided with a bore 11^a opening through the bottom and one side of said plug, whereby when said plug is screwed down tight, as in Fig. 3, the passage of air through opening 6^a will be pre-

vented, but when the plug is screwed outwardly sufficiently far air may enter reservoir 5 through bore 11^a. By unscrewing plug 11 so that air may enter the reservoir said reservoir 5 may be filled by screwing rod 10 outwardly and pouring the fluid into chamber 8, which will pass thence into the reservoir. If preferred, however, the reservoir may be filled through the opening 6^a, in which case the plug 11 may be removed, or, if preferred, a screw-cap 12 may be provided on neck 6^b, as in Fig. 5.

Within chamber 8 is a tube 13, that is shown extending nearly to the top of said chamber and at its lower end opens through the partition 3, and at 14 is a wick that passes through tube 13, preferably extending therefrom into chamber 4, part of said wick also being located in chamber 8 and extending down substantially to the bottom thereof, as in Fig. 3. By means of said wick the fluid from chamber 8 is by capillary action carried through tube 13 and delivered into chamber 4. Within chamber 4 is a fluid receiver and evaporator 15, which is shown in the form of a shell, having relatively large perforations 15^a, a space 4^a being provided between shell 15 and the walls of casing 1. The top 15^b of shell 15 is shown located below the upper edge 15^c thereof, providing a shallow pan or receiver 15^d for liquid delivered thereto by wick 13, the lower end of which wick is above such pan. At 16 is a drip-tube extending from the bottom 2 of casing 1 and communicating with space 4^a.

In the operation of this device the reservoir 5 is filled with liquid, the valve rod or stem 10 is raised to the desired height, so that liquid will enter chamber 8 to a height corresponding to the bottom of stem 10, and the wick 14 delivers such fluid to the pan or receiver 15^d, which fluid spreads out thereon and when said pan or receiver is filled the liquid overflows and slowly travels down the outer wall of shell 15, where the free circulation of air through the openings 15^a assists in causing relatively rapid evaporation of such fluid, and the excess liquid flows upon the bottom wall of chamber 4^a and passes through drip 16 to the place to be disinfected. The rapidity of delivery of fluid caused by wick 14 may be controlled at will by raising or lowering the valve rod or stem 10, whereby to increase or decrease the size of the opening or communication between reservoir 5 and chamber 8, to thereby regulate the height of fluid in said chamber, for when no air is admitted to the top of reservoir 5 the fluid in chamber 8 will only rise substantially to the height of the lower end of rod 10, even though the liquid in reservoir 5 is above the lower end of said rod, and the deeper wick 14 dips into fluid in chamber 8 the faster will be the feed of liquid by said wick and the less the wick dips into said fluid the slower will be the feed of fluid by the wick.

The details of construction shown and described may be varied without departing from the spirit of my invention.

Having now described my invention, what I claim is—

1. A disinfecting apparatus comprising a fluid-reservoir and a chamber for communication with each other, means to control at will the height of fluid in said chamber flowing from said reservoir, means to cause evaporation of fluid from said chamber, and a fluid-receiver beneath said reservoir and chamber provided with a top and perforated side walls beneath said top, substantially as described. 75

2. A disinfecting apparatus comprising a reservoir having its upper portion closed to the atmosphere and a chamber located side by side, a valve to control the flow of fluid from said reservoir to said chamber to regulate the height of fluid in said chamber, a fluid-receiver beneath said reservoir and chamber, and a wick to transfer fluid from said chamber to said receiver, substantially as described. 80

3. A disinfecting apparatus comprising a reservoir, a chamber and an opening connecting said reservoir and chamber, a vertically-disposed tube provided with openings in its sides for communication with the first-named opening, and with said chamber, a valve in said tube to control the flow of fluid from the reservoir through said openings to the chamber, and means to transfer fluid from said chamber for evaporation, substantially as described. 90

4. A disinfecting apparatus comprising a reservoir having means for normally closing its upper part from the atmosphere, a chamber having its upper part open to the atmosphere and communicating with said reservoir through an opening, a vertically-disposed tube in said chamber having openings in its sides for communication with the first-named opening, and with said chamber, a rod in said tube adapted to be moved to provide more or less communication between said chamber and reservoir, and means to transfer fluid from said chamber for evaporation, substantially as described. 100

5. A disinfecting apparatus comprising a reservoir having means for normally closing its upper part to the atmosphere, a chamber having its upper part open to the atmosphere and communicating with said reservoir through an opening, a tube in said chamber having openings for communication with the first-named opening, and with said chamber, a rod in said tube adapted to be moved to provide more or less communication between said chamber and reservoir, a tube opening through said chamber, and a wick located partly in said tube and partly in said chamber for delivering fluid from the latter, substantially as described. 115

6. A disinfecting apparatus comprising a fluid-reservoir and a fluid-receiving chamber, 130

means for regulating the flow of fluid from the reservoir to the chamber, a wick for transferring fluid from the chamber, and a receiver having a top and perforated side walls, upon 5 which top fluid is deposited by the wick and over which side walls the fluid flows from said top, substantially as described.

7. A disinfecting apparatus comprising a fluid-reservoir and a fluid-receiving chamber, 10 means for permitting the flow of fluid from the reservoir to the chamber, a wick for transferring fluid from the chamber, and a receiver having a top below the upper edge of the receiver forming a shallow pan to receive 15 fluid from said wick, the side walls of said receiver being perforated to cause evaporation of fluid flowing over from said edge, along said walls, substantially as described.

8. A disinfecting apparatus comprising a 20 casing having a fluid-reservoir, a fluid-receiving chamber for communication therewith, said casing having perforations below the reservoir, a fluid-receiver below the reservoir

having an imperforate top and the side walls of which are perforated, a wick for transferring fluid from said chamber to said receiver, a space being formed between the perforated walls of the casing and said receiver, and a drip communicating with said space, substantially as described.

9. A disinfecting apparatus comprising a fluid - reservoir and a fluid - receiving chamber, means for permitting the flow of fluid from the reservoir to the chamber, a wick for transferring fluid from the chamber, and a 35 receiver having a top and side walls to receive fluid from the wick, which fluid overflows from said top along the wall of the receiver, a perforated casing around said receiver providing a space, and an outlet communicating 40 with said space, substantially as described.
